[57] CLAIM

The ornamental design for a rotary lawn edger, trimmer
or similar article, substantially as shown and described.

DESCRIPTION

FIG. 1 is a side elevational view of a rotary lawn edger,
trimmer or similar article embodying my new design;

FIG. 2 is a front elevational view thereof;

FIG. 3 is a top plan view thereof;

FIG. 4 is a bottom plan view thereof; and

FIG. 5 is an isometric view thereof.

The handle has been omitted in FIGS. 3 and 4 for con-

venience of illustration.

FIG. 1

FIG. 2

FIG. 3

FIG. 5
